UNITED STATES PATENT OFFICE.

THEODORE W. FOSTER, OF PROVIDENCE, RHODE ISLAND.

DESIGN FOR A HANDLE FOR BUTTON-HOOKS OR SIMILAR ARTICLES.

SPECIFICATION forming part of **Design No. 25,262**, dated **March 24, 1896.**

Application filed February 12, 1896. Serial No. 579,089. Term of patent 7 years.

To all whom it may concern:

Be it known that I, THEODORE W. FOSTER, a citizen of the United States, residing at Providence, in the county of Providence and State 5 of Rhode Island, have invented and produced a new and original Design for a Handle, of which the following is a specification, reference being had to the accompanying drawings, forming part thereof.

- 10 Figure 1 is a side view of my newly-designed handle, showing the same connected to a button-hook, the outline of a paper-cutter being shown in broken lines. Fig. 2 is a sectional view of the handle on the line A B of Fig. 1.
- 15 The leading feature of my design consists in the peculiar raised foliated scrolls at each end of the handle, from which pointed plates extend along the center of the handle in opposite directions.
- 20 The lower end of the handle is formed into the annular bead 3, above which the handle is contracted in a concave line, which meets with the convex enlargement 4 ornamented with the foliated ends 6 6 of the beaded edges
- 25 7 7. From this lower ornamentation the pointed plate 8, having a graduated bead ornamentation, extends upward. The handle

expands gradually in width, the beads 7 7 on the edges enlarge until they merge into the raised foliated scrollwork 9, which incloses 30 the panel 10 on the upper end of the handle, the extreme upper end being ornamented by a group of three scrolls curved upward from the foliated scrollwork 9, and from the lower portion of the scrollwork 9 extends the pointed 35 plate 12 having a central line of graduated beads. The long irregular panel 13 of plain convex surface extends from the upper to the lower ornamentations of the handle.

The section of the handle, as shown in Fig. 40 2, has two convex sides connected with two narrow slightly-convex edges approximately forming an oval with somewhat flattened ends.

What I claim is—

45 The design of the handle as herein shown and described.

In witness whereof I have hereunto set my hand.

THEODORE W. FOSTER.
